George W. Richards

Felted Patent

The Feltingale referred to in these Felted Patent and making part of the same containing a description in the words of the said George W. Richards of his improvement in fulling cloth by the use of steam.

It has hitherto been the custom to prepare cloth in soap for fulling, by this process we are enabled to full cloth without the use of soap at all in a much shorter time and in much greater perfection as follows. 1st. After the cloth is taken out of the soap the cloth is put into common stocks which are used for the purpose of retaining the steam & is then placed in the usual mode. 2^d. The cloth is then wet with pure water and a small quantity of steam is introduced sufficient for heating it to a proper standard. The mill is then put in motion & the cloth is now handled as is customary. 3rd. By the above process the cloth becomes fuller & shrinks to a proper condition for drying in one third of the usual time required by fulling with soap. It also becomes much firmer & deeper to better advantage, besides it retains the entire colour of the blue & all other colour is that of soap before fulling; whereas by the old process considerable of the colour is lost. & the consequence of this mode the cloth works much easier in the mill & requires less force to propel the mill. 4th. The inventor applies to procure his steam in the customary mode he however reserves to himself the right of improvement both in procuring & introducing it in this method of fulling cloth, and as other modes of heating may be introduced besides that of steam, also perhaps with less convenience, the inventor also would reserve to himself the right of preparing cloth for fulling by any process of heat whatever, except by the natural heat occasioned by the motion of the mill. After the inventor reserves to himself the right of using any materials which have heretofore been used in fulling in aid of his plan if the case require.
